UNITED STATES PATENT OFFICE.

EDWARD B. YOUNG, OF OKMULGEE, OKLAHOMA, ASSIGNOR TO A. R. BRADSHAW, OF OKMULGEE, OKLAHOMA.

WINDOW-PULLEY.

1,215,231.

Specification of Letters Patent. Patented Feb. 6, 1917.

Application filed January 7, 1916. Serial No. 70,836.

To all whom it may concern:

Be it known that I, EDWARD B. YOUNG, a citizen of the United States, residing at Okmulgee, in the county of Okmulgee and State of Oklahoma, have invented new and useful Improvements in Window-Pulleys, of which the following is a specification.

This invention relates to pulleys and more particularly to sash cord pulleys.

10 The primary object of the invention is the provision of a device of this character which is arranged for convenient mounting upon a window-stile and is especially constructed to prevent the sash cord and window-stile 15 from binding during the action of the raising or lowering the windows, and further prevents the escape of the sash cord from said pulley, and further to so construct the mounting for the pulley to facilitate a ready 20 and quick adjustment of the same to the window-stile, and still further to so form the mounting or shell whereby its accidental displacement and rotation with respect to the window-stile is prevented.

25 With the above and other objects in view, the invention consists in the novel features, details of construction and combination of parts which will hereinafter be more fully set forth, illustrated in the accompanying 30 drawing and pointed out in the appended claims.

In the drawing:

Figure 1 is a front elevation of the pulley fitted to a window-stile;

35 Fig. 2 is a central longitudinal sectional view therethrough;

Fig. 3 is a transverse sectional view of the device; and

40 Fig. 4 is a perspective view of the improved pulley removed from the casement.

Referring more specifically to the drawing, in which like reference characters refer to corresponding parts in the several views, 5 denotes a shell constructed from an integral piece of sheet metal and gradually decreasing in diameter throughout its longitudinal extent to form the shell of a tapering formation and providing the same with an enlarged open front end 6 and a contracted discharge end 7, the contracted rear end being depressed at right angles with respect to the front end, owing to the fact that the shell is of substantially elbow shape.

50 The contracted or discharge end 7 is flared, as better shown in Fig. 2 of the drawing, to

prevent the cutting of the sash cord and the like during the raising or lowering of the windows. The walls of the shell forming the enlarged front opening thereof are thickened at diametrically opposite points 60 as at 8 for the purpose of reinforcing the shell. A grooved pulley 9 occupies the space between the thickened portions 8 of the casing and is rotatably mounted upon the spindle 10. The enlarged open end 6 of the shell is formed with an annular circular flange 11 which serves as a stop when the shell is in applied position and limiting the insertion of the shell within the opening 12 of the stile 13. A pair of ribs 14 is formed integral with the shell and is disposed longitudinally thereof on the upper and bottom surface thereof and arranged at diametrically opposite points, said ribs adapted to engage with the pair of diametrically opposed V-shaped recesses of the opening 12 whereby when the shell is inserted in the window casement the engagement of the ribs with said grooves prevents any accidental rotation thereof. The said thickened portions 8 of the shell 70 aside from serving as a reinforcement therefore also tends to accurately position the groove of the pulley in longitudinal alignment with the contracted rear end 7 of the shell whereby preventing any binding action 75 of the cord with the inner contour of the shell when it is desired to manipulate the windows. The underneath surface of the shell at a point to one side of and in spaced parallelism with the lowermost rib is a slot 80 15 which permits of the insertion therethrough of a fastener 16 in the form of a nail or the like whereby the shell will be prevented from any outward movement 90 with respect to the window casement and retain the same flush with the window grooves 95 at all times and prevent the breakage thereof by the contact of the same with the windows during the hoisting or lowering action 100 thereof.

From the foregoing description taken in connection with the accompanying drawing, the advantages of construction and of the method of operation will be readily apparent to those skilled in the art to which the invention relates, and while I have described the principles of operation of the device together with the device which I now consider to be the best embodiment thereof, 105 I desire to have it understood that the de- 110

vice shown is merely illustrative and that such advantages may be made when desired as are within the scope of the claim appended hereto.

5 I claim:

A sash cord pulley comprising a shell tapering throughout its longitudinal extent to provide the same with an enlarged front end and a contracted rear end, the contracted rear end of the shell being disposed at right angles with respect to the enlarged front end thereof, and flared, an annular flange formed on the enlarged front end of said shell, ribs formed on the outer periphery of the shell and extending longitudinally thereof, the walls of the shell forming

the enlarged front opening thereof being provided with thickened portions serving as a reinforcement therefor, a grooved pulley journaled within the thickened walls, the 20 said thickened portions of the casing retaining the pulley in longitudinal alinement with the flared contracted rear end of the shell, substantially as and for the purpose specified.

25 In testimony whereof I affix my signature in presence of two witnesses.

EDWARD B. YOUNG.
